UNITED STATES PATENT OFFICE.

WILLIAM L. DOUGHTY, OF OSHKOSH, WISCONSIN.

MEANS FOR BRIDGING OVER FIRE-HOSE.

SPECIFICATION forming part of Letters Patent No. 738,170, dated September 8, 1903.

Application filed November 28, 1902. Serial No. 183,085. (No model.)

To all whom it may concern:

Be it known that I, WILLIAM L. DOUGHTY, residing at Oshkosh, in the county of Winnebago and State of Wisconsin, have invented **5** a new and useful Improvement in Means for Bridging Over Fire-Hose, of which the following is a description, reference being had to the accompanying drawings, which are a part of this specification.

10 My invention has relation to improvements in means for bridging over fire-hose.

In cases of fire great trouble and inconvenience are occasioned by reason of the fire-hose extending across the roadway, and this **15** trouble and inconvenience are greatly enhanced in the case of thoroughfares equipped with street-railway tracks or steam-railroad tracks, as the cars are necessarily prevented from continuing their travel and are consequently held up for an indefinite time, thereby in the case of street-cars completely disorganizing the schedule and in the case of steam-cars delaying the arrival of a train at its destination for a long period.

25 It is the primary object of my invention to provide a simple construction involving the employment of supplemental rails which may be quickly adjusted to the rails proper of a track and bridge over the fire-hose extending transversely over a street or thoroughfare, and thereby permitting of the continuing of the travel of the cars with but a minimum loss of time.

With the above primary object in view the **35** invention consists of the devices and parts or their equivalents, as hereinafter more fully set forth.

In the accompanying drawings, Figure 1 is a plan view of my improvements adjusted to **40** a track. Fig. 2 is a view looking on the inner side of one of the rails equipped with my improved supplemental rail, the cross-rod being in section. Fig. 3 is a cross-section on the line 3 3 of Fig. 2. Fig. 4 is a cross-section on the line 4 4 of Fig. 2. Fig. 5 is a detail view of one of the wedges looking on the inner side thereof. Fig. 6 is a cross-section on the line 6 6 of Fig. 2, and Fig. 7 shows a modification of the wedging mechanism.

50 Referring to the drawings, the numerals 7 7 indicate the two rails of an ordinary railroad-track, and 8 8 the two supplemental

bridging-rails, which are adapted to be detachably adjusted to the top or tread of the main rails. These supplemental rails are **55** widest or highest at their centers and gradually taper downwardly to their ends, so that when adjusted to the main rails a car will gradually ride up from the main rails onto these supplemental rails and then gradually **60** ride down again onto the main rails. Each of these supplemental rails is provided at a desired point between its ends, preferably at a medial point thereof, with one or more recesses 9, extending upwardly from the lower **65** edge of said supplemental rail, the recesses of the two supplemental rails being preferably opposite each other, so that they may conveniently receive therein a line of hose extending across the track. In the accompanying drawings I show each supplemental rail as provided with two of the recesses, and each recess is of sufficient width to accommodate two lines of hose.

Any desirable means for detachably securing the supplemental rails to the tread of the main rails may be provided, and in the accompanying drawings I have shown several devices for this purpose and which will now be explained. One of the means illustrated **75** 80 consists of elongated flanges 10, rigid with the inner side of each supplemental rail and disposed at suitable distances apart. The lower edge of each flange extends below the lower edge of the supplemental rail and bears **85** against the inner side of the tread of the main rail. It is firmly secured to said tread by means of a set-screw 11, which turns through the flange, and its inner end impinges against the tread. If preferred, a plurality of these set-screws may be employed **90** for each flange. While I have only shown these flanges on the inside of the supplemental rails, yet, if desired, they may also be arranged on the outside of said rails and **95** bear against the outer sides of the treads of the main rails. Under this construction the flanges would straddle the treads of the main rails.

I furthermore show in connection with my **100** invention a means for securing the supplemental rails to the main rails, which is only applicable in cases where the main rails are not embedded. In large cities the rails are

generally embedded to such an extent that only the tread portions are above the surface. In such cases the devices about to be described would not be applicable. In 5 smaller cities and towns, however, the rails are frequently laid without embedding the same, and in these instances the construction about to be described will answer admirably. This construction consists of wedging mechanism. (Illustrated in detail in Figs. 4 and 5.) One portion of the wedging mechanism consists of a vertically-disposed member 12, provided at its lower end with a hook 13, which is adapted to extend under the 10 tread of the rail. The edge of the hook which engages the under side of the tread is preferably toothed or serrated, as most clearly shown in Fig. 5, in order to firmly bite the under surface of the tread. The upper portion 15 of the member 12 is reduced to form an upwardly-extending stem 14, which stem passes through an opening 15 in a horizontal member 16, said horizontal member extending through an opening 17 in the supplemental 20 rail. The member 12 is locked in the opening 15 by means of a wedge-key 18, extending through an elongated opening 19 in the stem 14. The length of the opening 19 is prolonged a sufficient distance beyond the width of the key as 25 to enable the key to engage the opening notwithstanding any variations in the width of the treads of the main rails. The horizontal member 16 is further retained in the opening 17 of the supplemental rail by means of a 30 wedge-key 20, passed through an opening 21 in the outer projecting end of said horizontal member 16 and bearing against the outer side of the supplemental rail. This opening 21 is sufficiently elongated to permit the 35 key to engage the opening notwithstanding variations in the width of the supplemental rail. If desired, another vertically-disposed member similar to 12 may be arranged against the outer side of the supplemental rail and its 40 hooked lower end extend beneath the tread on the outer sides of the main rail. This is 45 illustrated in the detail view Fig. 7, in which the horizontal member 16 instead of being provided with a horizontally-elongated opening 21 is provided with a vertical opening 22, through which the upwardly-extending stem 14 of the outer vertically-disposed or hooked member 12 passes, and another wedge-key 18 is passed through the elongated opening 19 50 of this outer vertically-disposed or hooked member 12.

In order to prevent the rails from spreading or being forced outwardly laterally, I employ a cross-tie rod or brace-rod 23. The opposite 60 ends of this rod are threaded and pass through openings in plates 24 24, disposed against the inner sides of the supplemental rails and extending downwardly against the inner sides of the treads of the main rails, being secured 65 to said sides of the treads of the main rails by means of set-screws 25, two of said screws being preferably employed for each plate.

Locking-nuts 26 26 are turned on each threaded end of the tie-rod, one of said nuts being turned on the outer extremity of each end of the rod and against the outer side of the supplemental rail and the other nut being turned on the threaded portion of the rod and against the plate 24. By the employment of this tie-rod it will be evident that an effectual brace 75 is provided which will prevent the supplemental rails from spreading or from being forced laterally outwardly, and the provision of the nuts 26 enables the tie-rod to be locked tightly at the properly-adjusted width to fit 80 the main rails. The tie or brace rod is preferably bent downwardly, so that the safety appliances attached to the front of street-cars or the cow-catchers of locomotive-engines may clear the rod. In cases where the main 85 rails are embedded the tie-rod may be turned upwardly slightly, so that the lower or depressed portion thereof will rest on the surface of the embedding substance.

While I prefer to employ the tie-rod above 90 described, yet I do not wish to be understood as limiting myself thereto, inasmuch as the same may be entirely omitted without departing from the spirit and scope of my invention. It is preferably used, however, as it is obvious 95 that it adds to the efficiency of the device. I also wish it understood that, if desired, the supplemental rails may be secured to the main rails merely by the employment of the elongated flanges 10, arranged either on the 100 inside or on the outside of the supplemental rail or on both sides of said rails. I also wish it understood that these elongated flanges 10 105 may be omitted and merely the wedging mechanism employed, or the elongated flanges 10 110 and the wedging mechanism may be employed together in one structure, and in any case the tie-rod may be utilized or not, as desired.

From the foregoing description it will be seen that I provide a device which may be 110 quickly adjusted to the permanent or main rails of a railroad-track and bridge over a fire-hose, and thereby avoid the delays which now occur in cases of fire when a hose is laid across a track.

My improved device may be carried in a 115 convenient place in a street-car, so as to be readily accessible to the motorman for adjustment to a track, or may be carried in the cab of a locomotive-engine, so that the engineer 120 may readily adjust it to the track. After the cars have traveled over the supplemental rails it is obvious that said rails may then be quickly detached from the main rails.

What I claim as my invention is—

1. In means for bridging over a fire-hose, the combination of fixed railway-rails, supplemental short rails each provided with a recess or recesses extending upwardly from its lower edge and adapted to receive therein a fire-hose extending over the fixed rails, and wedging mechanism for detachably securing each supplemental rail to a main rail, said wedging mechanism consisting of a vertically-dis-

posed member provided at its lower end with a hook fitting beneath the tread of the main rail, and provided near its upper end with an opening, a horizontal member passing through 5 an opening in the supplemental rail, and itself provided with an opening near one end and through which opening the vertically-disposed member extends, a wedge-key passing through the opening in the upper end of 10 the vertically-disposed member and bearing against the horizontal member, and means engaging and locking the opposite end of the horizontal member.

2. In means for bridging over a fire-hose, 15 the combination of fixed railway-rails, supplemental short rails each provided with a recess or recesses extending upwardly from its lower edge and adapted to receive therein a fire-hose extending over the fixed rails, and wedging mechanism for detachably securing each supplemental rail to a main rail, said wedging mechanism consisting of a vertically-disposed member provided at its lower end with a hook fitting beneath the tread of the main 20 rail, and provided near its upper end with an opening, a horizontal member passing through an opening in the supplemental rail, and itself provided with openings near opposite 25 ends, one of said openings having the vertically-disposed member passing therethrough,

and wedge-keys, one of said keys passing through the opening in the upper end of the vertically-disposed member and bearing against the horizontal member and the other key passing through the opening in the opposite 35 end of the horizontal member and bearing against the side of the supplemental rail.

3. In means for bridging over fire-hose, the combination of fixed railway-rails, supplemental short rails each provided with a recess or recesses extending upwardly from its lower edge and adapted, when the supplemental rail is adjusted to the main rail, to receive therein a fire-hose extending over the fixed rails, plates adjacent to the inner sides 40 of opposite supplemental and fixed rails, a cross-tie rod, having its opposite ends passing through said plates and through the supplemental rails, nuts on each end of the tie-rod, one of said nuts adapted to be turned against 45 the outer side of the supplemental rail, and the other nut against the plate, and set-screws turning through the plates and impinging against the main rails.

In testimony whereof I affix my signature 50 in presence of two witnesses.

WILLIAM L. DOUGHTY.
